UNITED STATES PATENT OFFICE.

ALBERT J. DREMEL, OF NEWTON, IOWA, ASSIGNOR TO THE MAYTAG COMPANY, OF NEWTON, IOWA, A CORPORATION OF IOWA.

FOLDING BASKET STAND.

1,413,710.

Specification of Letters Patent. Patented Apr. 25, 1922.

Application filed May 13, 1918. Serial No. 234,135.

To all whom it may concern:

Be it known that I, ALBERT J. DREMEL, a citizen of the United States, residing at Newton, in the county of Jasper and State of 5 Iowa, have invented new and useful Improvements in Folding Basket Stands, of which the following is the specification.

This invention relates to a basket stand of such nature that it may be either collapsed 10 or open up in position to support a basket, and more particularly to such stand mounted for swinging movement upon the side or end of a washing machine or the like.

In the operation of washing clothes it is a 15 question of prime importance to have a quickly available support upon which to rest the clothes basket. If such a support is not conveniently located there will be necessitated a considerable loss of time, due to 20 going a greater or less distance to obtain and bring forward into suitable position a stand for this purpose, and which stand when obtained will be of a clumsy nature and awkward to handle. This not only results in a very considerable loss of time, but 25 also imposes a task of no small degree upon the operator of the washing machine, which work is mostly done by women. These objections are obviated by my present invention. 30

Among the objects of this invention is to provide a basket stand of such nature that it may be folded up or collapsed when not in use, and readily opened up into extended 35 position when desired to support a clothes basket thereon; further to attach the same to a washing machine or the like in such manner that it may be immediately pulled out into extended position when required for 40 use, and folded back out of the way when not in use; further to provide novel means for swingingly mounting the stand to the washing machine or the like to accommodate swinging in a horizontal plane; to provide 45 novel means to permit the collapsing of the stand when not in use, and also to rigidly brace the parts of the stand when the same is being used to support a basket; further to provide novel means for locking the stand in 50 either distended or collapsed position; further to so construct the bracing means that a movement between two of the elements of the stand will produce a corresponding movement between every other two of the

same; and such further objects, advantages 55 and capabilities as will more fully appear.

My invention further resides in the combination, construction and arrangement of parts illustrated in the accompanying drawings, and while I have shown therein a preferred embodiment of my invention I desire 60 the same to be understood as illustrative only, and not as limiting the scope of my invention.

In the drawings:

Fig. 1 is a plan view of my improved basket stand in open position, and showing the same attached to a washing machine or the like.

Fig. 2 is a side elevation of Fig. 1.

Fig. 3 is a view similar to Fig. 1, but showing the stand in a collapsed position.

Fig. 4 is a side elevation looking at the outer face of the collapsed stand.

Referring to the drawings, it will be seen 75 that my improved basket stand comprises the horizontally extending bars or members 1, and the vertically extending legs 2 secured to the outer ends of the bars 1. 3 designates a portion (which may be the end 80 side or any other suitable portion) of a washing machine or the like to which the stand is pivotally mounted. Secured to the corner of the portion 3 is the angle 4, carrying an outwardly extending ring-like projection 5, which may be suitably formed by giving the desired curvature to a rod or the like screwed into this bracket. The inner ends of the bars 1 are perforated at 6, and through these perforations extends the 90 ring-like projection 5, as clearly shown in Figures 1, 2 and 3. From this construction it is seen that the bars 1 may be moved either towards or away from each other at their outer ends, such movement being accommodated by a sliding of the inner ends of the bars 1, upon the ring-like projection 5. Any other suitable form of pivotal mounting may however, be substituted for the construction shown if desired, the essential idea being to 100 pivotally mount the members 1 upon the support 3 in such manner that they may be either swung together against the side of the support, or swung away from each other in order to present a surface upon which a basket or the like may be positioned.

Secured to the outer end of the bars 1, by means of rivets or the like 7, are the

brackets 8, to which brackets are secured the downwardly extending legs 2, and which legs are each provided adjacent their lower ends with the longitudinally extending slots 5 10. Extending between each pair of legs 9 are the crossed bars 11 and 12, which are pivotally connected together midway of their length by the pivot 13. Each of the bars 11 is pivoted at 14 to the leg 9, and at 10 its lower end is provided with the projection 15 extending through the slot 10, which 70 projections may be in the form of a suitable bolt, rivet or the like. A similar construction is effected in the case of the bars 12, 15 the upper end of each being pivotally connected at 16 to the legs 9 and provided at the lower end with an aperture through which also passes the projection 15 in such manner that the bars 11 and 12 will be pivotally connected together thereon. From 80 this construction it will be seen that as the legs 9 are pushed towards each other, (assuming them to be in the position illustrated in Figure 2), the bars 11 and 12 will swing 25 upon the pivots 14 and 16, and by virtue of the pivot 13 the lower end of each of these bars will move downwardly, thus causing the projections 15 to follow the slots 10 and rest when the legs are brought together at 30 or near the lower end of these slots. The 90 projections 15, which are located in each of the end legs designated *a* and *b* are provided with a thumb nut 17 by virtue of which the legs may be locked in either open or closed 95 position by merely tightening this nut.

It will thus be seen that the braces between the legs 9 are arranged in lazy-tong fashion, the result of which is that movement of any two of the legs towards or away 40 from each other will produce a corresponding and an equal movement between every other two of the legs, thus making possible a structure which can be easily and quickly thrown into either open or collapsed position 45 and by simply turning the thumb nuts 17 securely locked in such position. By arranging the stand at the end or side of the washing machine or the like, it can be readily collapsed and swung against the washing 50 machine or the like so as to be out of the way and permit free movement around the same; and when it is desired to place the basket stand in operative position for the reception of a clothes basket or the like all 55 that is necessary is to grasp one of the bars 1, or legs 2 and move the same into open position, the other bars and legs simultaneously swinging into such open position by virtue of the lazy-tong construction described 60 above, after which the thumb nut 17 may be tightened and the stand thus made rigid for use. After serving its purpose it may be quickly and easily collapsed against the side of the washing machine or the like 65 by following reverse operations.

Having now described my invention:
I claim:

1. In a basket stand a plurality of vertical legs, a top member secured at right angles to each of said legs, said top members converging toward their rear ends at which point they are pivotally connected for swinging upon a support, said legs each having a longitudinal slot therein, a pair of crossed bars pivotally connected together midway of their 75 length and extending between said legs respectively, the upper ends of said bars being pivotally connected to said legs and the lower ends having projections slidably mounted in said slots, means on the lower and outer 80 end portion of each of the end pairs of crossed bars for locking the projection thereof in adjusted position in its respective slot whereby to lock said stand in open position.

2. In a basket stand a support, a ring-like projection on said support, a plurality of bars each having one end slidably mounted on said ring-like projection whereby their outer ends may be swung towards or away 90 from each other said outer ends each having a downwardly extending leg, a longitudinal slot in each of said legs, a pair of pivotally connected crossed bars extending between said legs, said crossed bars having their upper ends respectively pivoted to the adjacent leg and having at their respective lower ends a projection slidably engaging said slots, and means on the projections slidably engaging the slots of the end legs for locking the 100 stand in either open or closed position.

3. In folding basket stand apparatus a support, a plurality of horizontally extending arms each mounted for swinging movement on said support whereby they may be 105 swung toward or away from each other at their outer ends, a leg depending from each of said outer ends and having a longitudinal slot therein, a pair of pivotally connected crossed arms extending between each pair of legs, said crossed arms being each pivotally connected at one end to the adjacent leg and at its other end having means slidably mounted in said slot, and means for locking one or more of said slidably mounted means against 110 movement in its respective slot whereby said stand may be locked in either open or closed position.

4. In a folding basket stand a plurality of diverging arms adapted to be pivotally mounted at one end upon a support whereby they may be swung toward or away from each other, a depending leg on each of said arms, means connecting said legs to brace them and yet effect their movement toward or away from each other in equal amounts upon changing the distance between any two of them, and means for locking said legs in any desired separated position.

5. A folding basket stand adapted to be 130

swingingly mounted upon a washing machine or the like, and comprising a plurality of diverging arms so connected together at one end that they may be swung toward or 5 away from each other, a depending leg on each of said arms, lazy-tong connections between each pair of said legs whereby movement between any two of said legs will effect an equal movement between every other two, 10 and means for locking said legs in any adjusted position.

6. A folding basket stand adapted to be swingingly mounted upon a washing machine or the like, and comprising a plurality 15 of members connected for swinging movement toward and away from each other, means connecting said members in a plurality of interconnected pairs whereby movement between any two will produce an equal 20 movement between every other two, and means for locking said members in either open or closed position.

7. In combination a support, a basket stand pivotally mounted on said support for 25 swinging movement in a horizontal plane and comprising a plurality of relatively pivotally connected parts, means for causing the parts of said stand to swing open upon their pivot to hold a basket or to swing in collapsed position against said support, and 30 means to lock said parts in either distended or collapsed position.

8. In combination a support, a collapsible basket stand mounted on said support for 35 swinging pivotally in a horizontal plane and comprising a plurality of pairs of relatively

pivotaly mounted horizontal supporting members, means to effect the distension or collapse of said stand, and means to lock said stand in either distended position or collapsed position against said support. 40

9. The combination of a support adapted to be carried by a washing machine and a collapsible clothes basket stand mounted on said support for swinging movement in a 45 horizontal plane substantially about a pivotal point, said stand comprising arms pivotally mounted at one end and otherwise interconnected so that when there is swinging movement of one there will be a like movement of all and being adapted to support a clothes basket for use in conjunction with the washing machine. 50

10. The combination of a support, adapted to be carried by a washing machine and to 55 pivotally support a clothes basket stand adjacent the washing machine, and a clothes basket stand pivoted on the support for swinging movement in a horizontal plane, and adapted to support a clothes basket adjacent the washing machine, said stand comprising a series of arms pivoted at one end and interconnected so that they will be simultaneously collapsed or extended. 60

In witness whereof I hereunto subscribe 65 my name to this specification in the presence of two witnesses.

ALBERT J. DREMEL.
